UNITED STATES PATENT OFFICE.

JOHN ST. LEGER MCGINN, OF SHAWINIGAN FALLS, QUEBEC, CANADA.

TIDE MOTOR.

Application filed November 1, 1920. Serial No. 421,118.

To all whom it may concern:

Be it known that I, JOHN ST. LEGER MCGINN, of the town of Shawinigan Falls, Province of Quebec, Dominion of Canada, a subject of the King of Great Britain, have invented certain new and useful Improvements in Tide Motors; and I do hereby declare that the following is a full, clear, and exact description thereof.

10 The invention relates to the type of air compressors described in my pending United States application No. 391,849 and Canadian application No. 242,189 and has for its object the general improvement of hydraulic air compressors as well as to adapt this principle to the development of power from the action of the tides.

To this end the present invention consists of a basin formed at tide water by means 20 of a dam or sea wall having a height slightly greater than the highest tide.

This wall has a gate at approximately the lowest water level which may occur within the basin, such gate opening inwardly to admit water to the basin when the sea level is 25 higher, and being closed by any tendency of the water within the basin to flow outwardly through it.

From a point within the basin a shaft 30 into which an upwardly extending stand pipe is built is sunk to the desired depth, from the bottom of which a horizontal tunnel leads to a second shaft which has free communication with the sea outside the sea 35 wall; the stand pipe, the shaft, the tunnel and the second shaft providing a continuous passage way for water from the basin to the sea.

The upper end of the stand pipe is enlarged to form the outer wall of a head piece 40 concentrically placed in which is an air chamber having a closed bottom and extending upward above the highest water level.

The lower portion of this air chamber and 45 the outer wall of the head piece form an annular water duct.

The air chamber is provided with nozzles 50 fixed in its wall and extending outwardly into the water duct, each adapted to present an expanding suction space acted upon by the water which flows downwardly through the water duct and draws bubbles of air from the nozzles.

The tunnel at one point is enlarged to 55 form an air separating chamber, from which

a pipe is carried upward to a point above the sea floor, whence one branch extends to an accumulating tank resting upon the sea floor at the same level as the separating chamber, while a second branch communicates 60 through a weighted check valve with the storage tank whence the service pipe is supplied with compressed air at even pressure.

For full comprehension, however, of my invention reference must be had to the accompanying drawing in which similar reference characters indicate the same parts and wherein:

Figure 1 is a vertical sectional view taken on line 1—1 Figure 2 of a single basin tidal 70 motor constructed according to my invention;

Figure 2 is a plan view thereof;

Figure 3 is a detail end view of one of the air suction nozzles;

Figure 4 is a longitudinal sectional view taken on line 4—4 Figure 3;

Figure 5 is a horizontal sectional view taken on line 5—5 Figure 1, and

Figure 6 is a detail sectional view of the 80 weighted check valve in the air supply pipe.

The bottom of the sea is indicated at 2, the sea wall, preferably of reinforced concrete at 3, the inwardly opening gate at 4, the basin at A, the stand pipe at 5, the tunnel at 7, the separating chamber at 8, discharge shaft at 9, air pipe at 10 with branches 12 to the accumulating tank and 13 to the storage tank. The accumulating tank is shown at 14 with blow off at 15, the storage 90 tank at 16, the weighted check valve at 17 and the service pipe at 26. Of the head piece the outer wall is indicated at 18, the air chamber at 19, annular water duct at 20, and air suction nozzles at 21. Of the air 95 nozzles 24 indicates the socket plug which may be screwed into the wall of the air chamber from within, 22 the short pipe, 23 the flap valve, and 25 the angular louver.

I have devised a fixed head piece to operate under conditions of changing head-water levels and having a long circumferential line or lip in proportion to the sectional area of its water content to provide a more free entrance for the head water 105 while avoiding central vortex effects. The head piece consists of two cylinders 18 and 19, one within the other forming a water duct 20, between them for the down-flow of the head-water.

The outer cylinder 18 is an enlarged upward extension of the stand pipe and its lower end is of truncated conical form, the truncated apex being connected with the upper portion of the stand pipe.

The inner cylinder 19 which constitutes the air duct has a closed bottom of conical form the angle of which is more obtuse than the outer cone for the purpose of presenting a downwardly expanding water passage in order to obtain suction. This air duct extends upwardly above the highest water level.

The wall of the air duct is fitted with a number of nozzles 21 consisting of short pipes 22 of relatively small bore, each carried by a plug 24 in which it may be screwed, the outer end of the pipe having a flap valve 23 adapted by a float 230 to check the inward flow of the water while allowing free outward flow of the air. This float 230 is so positioned that when the water rises into engagement therewith it closes the valve 23 and when it is clear of the water it acts as a counterweight adapted to produce a slight opening movement of the valve. The pipe 22 is covered by a louver 25 projecting outwardly into the duct to within close proximity of its outer wall.

This louver is of angular form to offer minimum resistance to the downward flow of the water while the long edge extending along each side and the outer end of it, over which the water flows, tends to set up a partial vacuum at the underside of the louver, thus imparting to it the character of a suction tube and increasing the amount of air which would otherwise be drawn through the pipe 22.

A storage tank 16 preferably resting upon the sea wall 3 has connection by the pipes 13, 10 and 12 with both the separating chamber 8 and the accumulating tank 14. The pipe 13 is fitted with a weighted check valve 17 situated near its point of connection with the tank 16.

The accumulating tank 14 is preferably built of reinforced concrete and rests upon the sea floor at an even depth with the separating chamber 8 so that the air pressure is the same in both.

The highest tide level in the basin is indicated at B and the lowest tide level in the basin at C which it will be noted is above the top of the pipe 18. The lowest tide level outside the basin is indicated at D. From B to C indicates the amount of water used through the compressor before the incoming tide again reaches the level of C and begins to supply new water to the basin.

Operation.

In the operation of my plant the rising tide opens the gate 4 and enters the basin. A till, at high tide, the basin is filled to the

level indicated at B. At this stage the water within the basin is at even level with the tide and there is no action within the compressor and, the flap valves 21 being closed, the water is prevented from entering the air duct 19.

But, with the recession of the tide, the gate 4 is closed by predominance of pressure from within and the basin water owing to its restricted outlet through the tunnel 7 and shaft 9 is left at a higher level establishing a head equal to the difference between its level and that of the tide outside the sea wall.

Immediately the head is established the basin water flows down the water duct 20, and stand pipe 5 along the tunnel 7 and up the shaft 9 to the sea.

In its flow down the water duct 20 the water flowing over the louvers sets up a partial vacuum therein allowing the flap gates 23 to open, the suction causing an outward flow of air and the formation of bubbles which travel with the water in its downward flow to the separating chamber 8 where the air is trapped, the water passing up the discharge shaft 9 to the sea.

As the air is separated from the water in chamber 8 it displaces the water in pipes 10 and 12 and simultaneously accumulates in chamber 8 and accumulating tank 14, the water in the latter being expelled through blow-off 15. This accumulation will continue until the air pressure is sufficient to raise valve 17 at which point the air will pass into storage tank 16.

Owing to the fact that the discharge of the plant is in the open sea the pressure of the accumulated air varies with the tides, and in order to obtain a flow of compressed air at a constant pressure to tank 16 I adjust the weighted check valve 17 to the lowest effective pressure in the plant, which is the pressure of the lowest tide, thus maintaining a constant pressure in this tank.

The most effective driving head occurs when the tide is lowest and, as the incoming tide approaches the level of the water within the basin, that head is reduced until the down flow in the water duct is insufficient to draw air from the nozzles. The compressor thus ceases to operate until such time as the outgoing tide reestablishes sufficient head to again set up operating conditions.

There is also a margin of time before and after complete cessation of its operation when the compressor is not compressing sufficient air to equal the amount to be supplied, and there is also a time during the low stages of the tide when the compressor is furnishing compressed air in excess of such amount. It is the office of the accumulating tank 14, therefore, to receive and store such excess air and furnish it as required to carry over such times of insuf-

ficient power production, and together with the separating chamber, the reducing valve and the regulating tank to maintain a constant supply of compressed air at constant 5 pressure.

What I claim is as follows:

1. In an hydraulic air compressor of the type described, the combination of a vertically disposed water conductor having its 10 upper end of increased diameter; a vertically disposed air duct positioned within said enlarged upper end and providing a surrounding annular passage through the latter for the water, said duct having an open 15 upper end and a closed lower end, and a plurality of short air suction nozzles mounted upon said duct and projecting radially therefrom into said annular passage, and devices mounted upon the duct in position 20 overhanging said nozzles and adapted to increase the suction therethrough.

2. In an hydraulic air compressor of the type described, the combination of a vertically disposed water conductor having its 25 upper end of increased diameter; a vertically disposed air duct positioned within said enlarged upper end and providing a surrounding annular passage through the latter for the water, said duct having an open 30 upper end and a closed lower end, and a plurality of short air suction nozzles mounted upon said duct and projecting radially therefrom into said annular passage; louvers mounted upon the duct in position 35 overhanging said nozzles for the purpose of increasing suction through the latter, and valvular means preventing an inward flow of water through said nozzles.

3. In an hydraulic air compressor of the type described, the combination of a vertically disposed water conductor having its 40 upper end of increased diameter; a vertically disposed air duct positioned within said enlarged upper end and providing a surrounding annular passage through the latter for the water, said duct having an open upper end and a closed lower end, and a plurality of short nozzles mounted upon said duct and projecting radially therefrom 45 into said annular passage; louvers mounted upon said duct in position overhanging said nozzles for the purpose of increasing suction through the latter, and valvular means preventing an inward flow of water through 50 said nozzles; said valvular means consisting of a flap valve hinged upon the outer end of each nozzle; a float movable in unison with the said valve whereby the valve is closed when the float is engaged by the water and 55 when the float is clear of the water it acts as a counterweight producing a slight opening movement of the valve.

4. A tidal motor consisting of a basin separated from the open sea by a fixed wall 60 having a one-way port adapted to permit

inward flow of the water from the sea into the basin; an hydraulic air compressor consisting of a water conductor of substantially U-form extending beneath the said fixed wall one arm of which conductor communicates 70 with the basin and the other with the sea; an air duct mounted in position within said first-mentioned arm whereby the air is sucked therefrom into the descending water; an air separating chamber forming an upward extension of said water conductor between its arms; an air storage tank; and pipe adapted to conduct the air from said separating chamber into said tank, and an air accumulating tank located in position below the 80 level of the first mentioned tank and a pipe effecting communication between the accumulating tank and the first mentioned pipe.

5. A tidal motor consisting of a basin separated from the open sea by a fixed wall 85 having a one-way port adapted to permit inward flow of the water from the sea into the basin; an hydraulic air compressor consisting of a water conductor of substantially U-form extending beneath said fixed wall one 90 arm of which conductor communicates with the basin and the other with the sea, said first-mentioned arm having an enlarged upper end; an air duct positioned within said enlarged end and providing an annular 95 space within the arm for the passage of water therethrough, the upper end of said air duct being open and extending to a point above the highest water level within the basin and its lower end being closed, a plurality of nozzles mounted upon said air duct and projecting radially into said annular space whereby the air from the duct is 100 sucked into the descending water; an air separating chamber forming an upward extension off said water conductor between its arms; an air storage tank; a pipe adapted to conduct the air from the separating chamber to said tank, an air accumulating tank 105 submerged in the open sea and adapted to rest upon the sea floor, said last-mentioned tank having a blow-off adapted to permit the entry of water thereinto and to provide an outlet for such water when air is introduced into the tank, and a pipe effecting communication with the top of the interior of said last-mentioned tank and said first-mentioned pipe, the submerged tank being 110 located at a lower level than the first-mentioned tank.

6. A tidal motor consisting of a basin separated from the open sea by a fixed wall having a one-way port adapted to permit inward flow of the water from the sea into the basin; an hydraulic air compressor consisting of a water conductor of substantially U-form extending beneath the said fixed wall one arm of which conductor communicates with the basin and the other with the sea; an air duct mounted in position within said 115

first-mentioned arm whereby the air is sucked therefrom into the descending water; an air separating chamber forming an upward extension of said water conductor between its arms; an air storage tank and pipe adapted to conduct the air from said separating chamber into said tank; weighted check valve in said pipe, and an accumulating tank located in position below the level of the first mentioned tank and a pipe effect-

ing communication between the auxiliary tank and the first mentioned pipe.

In testimony whereof I have signed my name to this specification in the presence of two witnesses.

JOHN ST. LEGER McGINN.
